ULTRA HIGH FREQUENCY VIBRATOR

Hugo Benioff, Pasadena, Calif., assignor, by mesne assignments, to Submarine Signal Company, Boston, Mass., a corporation of Delaware

Application January 10, 1946, Serial No. 640,249

10 Claims. (Cl. 259—1)

1

The present invention relates to an ultra high frequency vibrator of the type disclosed in my copending application, Serial No. 606,498, filed July 23, 1945, and relates more particularly to improvements over the apparatus therein disclosed. One of the principal advantages in the present construction is that, in the present device, the insulating oil surrounding the oscillating element is sealed permanently rather than being sealed by a removable seal like a packing gland or a rubber gasket. The whole apparatus is placed under vacuum before filling to outgas the whole structure. The oil is heated to 100° C. under vacuum and then is permitted to fill the chamber to full atmospheric pressure, thus entirely exhausting the oil of air and gas. This has been found to be very important in the construction and operation of the present device.

A further advantage of the present apparatus is the form of the piezoelectric oscillating crystal which is used. In the present construction the crystal has a thin flange around its periphery by means of which it is held and supported and forms a seal for the insulating oil. The apparatus may be used for vibrating samples of materials of liquids or solids which are placed in a container which fits into the top of the device in a liquid coupling medium covering the electrode of the crystal but separated from the insulating oil. The apparatus may be used not only for laboratory work but also for industrial and commercial purposes.

Further advantages and merits of the present invention will be more fully described in the specification below in connection with the drawings showing an embodiment thereof, in which Fig. 1 shows a general vertical sectional view through the apparatus taken on the line 1—1 of Fig. 4; Fig. 2 shows a plan view as seen from the top of Fig. 1; Fig. 3 shows a section taken on the line 3—3 of Fig. 1; and Fig. 4 shows a view in vertical elevation of the device.

In the arrangement illustrated by the figures the liquid vibrator, as a whole, is supported by a flange 9 on the inner side of which is attached a flange 5 by means of a soft solder weld as indicated at 30. The collar 5 is provided with an inwardly extending shoulder or supporting ring 31 to which is attached a plate 32 by means of a series of screws 33 clamping the plate 32 to the shoulder 31 between which is a sealing gasket 18. The plate 32 has attached on its under side a downwardly extending cylindrical flange or collar 34 to which is attached in turn a heat resisting glass tube 12 or such other type of glass tube

2

as will not crack under changes in temperature. First a band of silver is fired on the ends of the glass tube which is then soldered by means of soft solder to the collar 34 at the top and the collar 34' at the bottom. Fitting over the ends of the glass tube 12 are small end fitting rings 10 and 10' which support the glass tube and to which the collars 34 at the top and 34' at the bottom are also soldered. The collar 34' at the base (Fig. 1) extends from the supporting base 35 on which also the ring 10' is supported. The supporting base 35 is formed with a cylindrical shell 36' which extends upwardly and supports the quartz crystal 368. The cylindrical shell 36' forming the chamber 36 is provided at the top with a narrow neck portion 37 and an end shoulder or corner 38 extending all the way around the neck 37 serving as a seal for the crystal 368. The crystal is retained in the shoulder 38 by means of soft solder of a suitable type. First a layer of silver is burned on the lower face of the crystal which serves as the lower electrode 39 and a base for soldering at the edge. The crystal 368 is formed of quartz or other suitable piezoelectric material with electrode 39 on the bottom surface of the crystal and an electrode 40 which is a thin metallic diaphragm separated from the top surface of the crystal by a thin oil film as will be explained later. This thin diaphragm forms an acoustic window whereby the vibrations are transmitted to the liquid chamber above it. The base member 35 mentioned previously is provided with air vents 11 extending from the outside of the device to the inside chamber 36. A bellows element 41 is attached to the bottom of the base 35 by suitable means such as soldering and a communicating passage 42 is provided through the base 35 to the chamber formed with a glass tube 12 on the outside and the cylindrical shell 36' on the inside which supports the piezoelectric crystal. This chamber 43 and the inside of the bellows are filled with insulating oil mentioned before which has been heated and cooled under vacuum for sufficient time to withdraw all of the gases contained in the oil. The oil of the chamber 43 surrounds the crystal 368 on its sides and forms the film on top of the crystal between the top crystal surface and the metal electrode and diaphragm 40. The upper part of the chamber 43 is separated from the liquid into which the sample to be vibrated is placed by the cylinder 44 positioned concentrically within the glass tube. The diaphragm 40 is attached by proper welding or otherwise to the bottom of the cylinder 44 which is provided with a rounded flange on its base.

The diaphragm 40 is preferably very thin so as to permit vibrations to pass through it unimpeded and may be of Monel metal or some similar element. The tube 44 may be of copper and of comparatively thicker dimensions as this element need not enter into the vibration and provides a path of high heat conductivity to carry heat away from the crystal. The top of the tube 44 rests in a shoulder in the plate 32 and has also an upwardly extending cylindrical portion 45, by means of which a seal is formed at the top of the chamber 43 with the downward flange 49 of the ring 48. In this construction the sleeve or collar 2 welded to the plate 32 is positioned concentrically with the various tubes and cylinders of the apparatus. The sleeve 2 is threaded at its top to receive a cap 6 provided with an inwardly extending flange and shoulder 47 on which the container or vessel 53 is placed. The sleeve 2 is recessed at its inner top edge to form a seat for the flanged member 48 which is welded to the sleeve 2. The member 48 has integrally formed with it the neck 49 abutting the collar 45.

Assembly is complete before the oil is introduced as otherwise the oil would be exposed to air which would greatly increase its tendency to form bubbles under the action of intense sound waves which would permit electrical breakdowns and decrease the efficiency of acoustic coupling. 16 is a valve for evacuating and filling the chamber.

It should be noted that surrounding the quartz crystal 368 is a mica ring 317 which is supported by means of three glass rods 13 which fit in recesses at the top in the under side of the plate 32 and at the bottom in the base 35. The length of the rods is such as to leave a small space at the top so as not to put pressure on the glass rods. Within the cylinder 44, which is closed at the bottom by the diaphragm 40 serving as an electrode for the quartz crystal 368, there is a liquid bath 52 which serves as an acoustic or vibratory coupling medium between the vibrations produced by the crystal and the sample container 53 the bottom of which is immersed in the bath. The sample container 53 is seated in the hole in the cap 6 and extends well down within the cylinder 44. The substance to be treated is placed within the container 53 the bottom of which is covered with a very thin diaphragm 54. The sample may be a liquid or whatever is desired to be treated with the vibrations produced by the device.

Electrical energy is conducted to the crystal in the manner similar to that in my copending application mentioned above. The glass tube and rods together with the liquid in the chamber 43 act as insulating elements between the two electrodes 39 and 40. Electrical energy is conducted to the electrode 39 through the cylinder 36', the base 35 and the outside protecting cover 55. The upper electrode 40 is grounded to the casing or supporting ring 9. The device is employed in the same manner as described in my above mentioned copending application and the frequency range of operation may be of the same magnitude.

Having now described my invention, I claim:

1. An ultra high frequency vibrator comprising a piezoelectric crystal having a thin peripheral flange, an enclosed cylinder having a seat formed around the periphery at one end to which the flange of the crystal is sealed, a heat resistant insulating tube surrounding and concentric with said crystal and cylinder providing the outer walls of an insulating oil chamber, a container con-

centrically positioned with respect to said tube forming a portion of the inner wall of said chamber, said container having a diaphragm sealed to the bottom thereof, said diaphragm extending over the front surface of said crystal with an oil film between the crystal and said diaphragm, means effecting a permanent seal at both the bottom and top of said chamber and insulating oil substantially free of gases extending throughout said chamber.

2. An ultra high frequency vibrator comprising a piezoelectric crystal having a thin peripheral flange, an enclosed cylinder having a seat formed around the periphery at one end to which the flange of the crystal is sealed, a heat resistant insulating tube surrounding and concentric with said crystal and cylinder providing the outer walls of an insulating oil chamber, a container concentrically positioned with respect to said tube forming a portion of the inner wall of said chamber, said container having a diaphragm sealed to the bottom thereof, said diaphragm extending over the front surface of said crystal with an oil film between the crystal and said diaphragm, means effecting a permanent seal at both the bottom and top of said chamber and insulating oil substantially free of gases extending throughout said chamber and cooling means extending into said chamber.

3. An ultra high frequency vibrator comprising a piezoelectric crystal having a thin peripheral flange, an enclosed cylinder having a seat formed around the periphery at one end to which the flange of the crystal is sealed by soft solder applied to burned on silver, a heat resistant insulating tube surrounding and concentric with said crystal and cylinder providing the outer walls of an insulating oil chamber, a container concentrically positioned with respect to said tube forming a portion of the inner wall of said chamber, said container having a diaphragm sealed to the bottom thereof, said diaphragm extending over the front surface of said crystal with an oil film between the crystal and said diaphragm, means effecting a permanent seal at both the bottom and top of said chamber comprising a thin flange extending upwardly from the top of said container, a collar concentrically positioned with respect to said container and forming a permanent seal at the outer side of said chamber, said collar having a seating recess at the top thereof, a ring having a downwardly extending flange positioned to adjoin the upwardly extending flange of said container, said ring being sealed in said seat and at the junction of the flange with the flange of the container.

4. An ultra high frequency vibrator comprising a piezoelectric quartz crystal having a thin flange at its peripheral edge, a cylinder closed at one end and exposed to the air having a thin section at its open end, means sealing said crystal at its thin section to said cylinder, means providing a sealed chamber having its axis parallel with the vibrational axis of said crystal and extending above and below the same, cooling means provided at the bottom of said chamber, said chamber having an acoustic window extending over the upper surface of said crystal and means forming a liquid bath over said window and on the inner side of said chamber a mica insulating ring surrounding said crystal and positioned over said flange, insulating means supporting said ring within said chamber.

5. An ultra high frequency vibrator comprising a piezoelectric crystal having a relatively

thinner flange at its peripheral edge, a cylinder closed at one end and vented through the walls thereof to the atmosphere, and opened at the other end, the wall section at the open end being thinner than elsewhere, means sealing said crystal at said thin flange to the thin wall section at said open end to close said open end, a hermetically sealed chamber disposed outside said cylinder and having said crystal and a portion of said cylinder as walls thereof, and an acoustic window as another wall thereof, a substantially gas-free insulating oil filling said chamber and thereby covering a surface of said crystal, said window being disposed to extend over said surface separated therefrom only by a film of said oil.

6. An ultra high frequency vibrator comprising a hermetically sealed chamber having a diaphragm as a wall member thereof, a substantially gas-free insulating oil filling said chamber, and a piezoelectric crystal positioned in such proximity to said diaphragm wall that said diaphragm wall may serve as one electrode of a crystal vibrating system.

7. An ultra high frequency vibrator comprising a hermetically sealed chamber having a diaphragm as a wall member thereof, a substantially gas-free insulating oil filling said chamber, a piezoelectric crystal positioned in such proximity to said diaphragm wall that said diaphragm wall may serve as one electrode of a crystal vibrating system, a second electrode attached to a surface of said crystal, and means providing electrical connections to said second electrode and to said diaphragm.

8. An ultra high frequency vibrator comprising a hermetically sealed chamber having a diaphragm as a wall member thereof, a substantially gas-free insulating oil filling said chamber, a piezoelectric crystal positioned in such proximity to said diaphragm wall that said diaphragm wall may serve as one electrode of a crystal vibrating

system, a second chamber outside of said sealed chamber and also having said diaphragm as a wall thereof, and an acoustic coupling medium in said second chamber, whereby acoustic energy is coupled from said crystal to said medium through said diaphragm.

9. An ultra high frequency vibrator comprising a hermetically sealed chamber having a diaphragm as a wall member thereof, a substantially gas-free insulating oil filling said chamber, a piezoelectric crystal positioned in such proximity to said diaphragm wall that said diaphragm wall may serve as one electrode of a crystal vibrating system, said chamber extending away from said diaphragm reentrantly as a cup with said diaphragm in the bottom thereof, and an acoustic coupling medium disposed in said cup.

10. An ultra high frequency vibrator comprising a hermetically sealed chamber having a diaphragm as a wall member thereof, a substantially gas-free insulating oil filling said chamber, a piezoelectric crystal positioned in such proximity to said diaphragm wall that said diaphragm wall may serve as one electrode of a crystal vibrating system, a portion of said chamber being in the form of a bellows.
